United States Patent Office

Des. 179,624
Patented Feb. 5, 1957

179,624

SLIP

Harvey Breitman, White Plains, N. Y., assignor to United Mills Corporation, a corporation of North Carolina

Application November 17, 1955, Serial No. 38,943

Term of patent 14 years

(Cl. D3—26)

Fig. 1.

Fig. 3.

Fig. 2.

What I claim is:

The ornamental design for a slip, as shown.
